UNITED STATES PATENT OFFICE.

CHARLES SUTTIE, OF ONEHUNGA, NEW ZEALAND.

ORE-CRUSHER.

SPECIFICATION forming part of Letters Patent No. 680,401, dated August 13, 1901.

Application filed July 12, 1901. Serial No. 68,027. (No model.)

To all whom it may concern:

Be it known that I, CHARLES SUTTIE, a subject of the King of Great Britain, residing at Onehunga, in the Provincial District of Auckland, New Zealand, have invented certain new and useful Improvements in Ore-Crushers; and I do declare the following to be a full, clear, and exact description of the invention, such as will enable others skilled in the art to which 10 it appertains to make and use the same.

The invention relates to an ore-crusher, and more particularly to that class of machines known in the art as "roller" crushing or grinding mills for crushing, grinding, or mixing mineral ore or other substances.

The object of the invention is to provide a machine of this character which will be simple of construction, durable in use, comparatively inexpensive of production, efficient in 20 operation, and one in which the crushing pressure is gradually increased and applied to the ore in its movement through the machine.

With these and other objects in view the 25 invention consists of certain novel features of construction and combination of parts, which will be hereinafter fully set forth.

In the accompanying drawings, Figure 1 is 30 an end elevation of my improved ore-crusher, showing parts broken away to more clearly illustrate the invention. Fig. 2 is a longitudinal vertical sectional view.

Referring to the drawings, 1 denotes the crushing-chamber, cylindrical in form and 35 disposed with its axis in a horizontal plane, and 2 denotes a supporting-base, to which the chamber is rigidly secured by links or other suitable means 3. The chamber is provided with end plates 4 and with sieves or gratings 40 5, which are bolted or otherwise secured to the ends of said chamber. The sieves or gratings are arranged at opposite ends of the chamber and to one side of a vertical line drawn through the axis of the chamber and may be 45 integral with or separate from the end plates. The chamber is provided with a feed-hopper 6 at the highest point in its periphery, into which the ore to be treated is fed.

7 denotes a drive crusher-roll, and 8 a drive-shaft to which it is fixed and which extends 50 through large openings 9, located centrally in the end plates 4.

10 denotes a series of rolls located within the chamber and arranged annularly about the drive-roll 7. These rolls are loose—*i. e.*, 55 have no journals—and are free to travel the annular race formed by the periphery of the roll 7 and the inner annular wall of the chamber. These rolls 10, when the crusher is in operation, travel around the center roll and 60 are of such number and of such diameter as not to fit tightly between the center roll and the interior wall of the chamber or against one another. In other words, sufficient slack or space is allowed between the loose rolls 65 and center roll and the inner annular wall of the chamber to prevent jamming of the loose rolls and to allow space in the interior of the chamber for receiving and carrying the material to be operated upon. By journaling 70 the axis of the center roll in the large bearing-apertures 9 of the chamber the effect will be to make the space between the periphery of the center roll and the inner annular wall of the chamber greatest at the top and lessening off on each side as the bottom is approached. The result is that the material becomes gradually reduced as it nears the bottom by reason of the decreasing distance 75 between the crushing-surfaces caused by the contraction of the space above referred to, and as the material approaches the lowest point of the chamber additional crushing pressure is applied to the material by reason of the fact that the weight or pressure of the 80 lowermost rolls 10 will be materially increased as each succeeding roll passes from the right-hand side of a vertical line drawn through the axis of the chamber to the left-hand side of said line. The drive-shaft 8 may be 85 weighted in any well-known manner to increase the pressing action of the drive-roll 7.

In operation power is applied to the drive-shaft to revolve the drive-roll 7. The motion of this roll bearing on such of the loose 90 rolls 10 as support its weight causes these loose rolls to move bodily in the same direction as the center roll is driven, and this action forces the loose rolls around the race, each loose roll in its travel taking the weight 95 of the center roll and a portion of the weight of the rolls above it. The material to be operated upon having been (when so required) reduced by stone-breakers or otherwise to a 100

size capable of being treated by this machine is fed through the feed-hopper and is carried around by the movement of the rolls and crushed between the rolls themselves 5 and against the inner annular wall of the chamber. The grinding power is exercised mainly, in fact almost entirely, on that side of the mill which carries the freshly-fed material, and such grinding power increases as 10 the material approaches the bottom of the chamber. After passing beneath the rolls at the bottom of the chamber the sufficiently-pulverized portion of the material is discharged through the sieves or gratings, and 15 such portion thereof as is insufficiently crushed is, by the continually-revolving action of the rolls, carried around and again comes under the grinding power of the crusher until sufficiently reduced.

20 It is of course understood that all the rolls are of such length that they will fit as close between the end plates 4 as is compatible with least friction against them when revolving. The rolls, in other words, are to be of 25 such length that when in motion they will revolve sufficiently freely to do their work without unreasonable waste of power by reason of friction of the end plates, while at the same time they will fit, without sacrifice 30 of such freedom of revolution, sufficiently closely to prevent excessive entry of grit or dust between the end plates and the ends of the rolls.

Various changes in the form, proportion, 35 and minor details of construction may be made within the scope of the invention without departing from the spirit or sacrificing any of the advantages thereof.

Having thus described my invention, what 40 I claim, and desire to secure by Letters Patent, is—

1. In an ore-crusher, the combination, with a cylindrical crushing-chamber provided with an inlet and an outlet, of a drive-roll mount-

ed in said chamber, and a series of loose rolls 45 located in the race of said chamber formed by the periphery of said drive-roll and the interior annular wall of said chamber and bodily movable about said race and driven by the action of said drive-roll, substantially 50 as set forth.

2. In an ore-crusher, the combination, with a cylindrical crushing-chamber provided with an inlet in its periphery and a grated outlet, of a drive-roll having its axis loosely mounted in the ends of the chamber to rotate and having a vertical play therein whereby the roll may assume an eccentric or concentric relation with the chamber, and a series of 55 loose rolls located in the race of said chamber formed by the periphery of said drive-roll and the interior annular wall of said chamber, and bodily movable about said chamber, and driven by the action of the drive-roll, substantially as set forth. 60

3. In an ore-crusher, the combination, with a cylindrical crushing-chamber provided with an inlet in its periphery, of sieves located in the ends of said chamber to the side of its axis, a shaft loosely journaled in the ends of 70 the chamber, and having a vertical movement therein, a drive crusher-roll fixed to said shaft, and a series of rolls loosely mounted within the chamber between the interior wall thereof and the periphery of the drive-roll and free to move around the chamber and driven by the action of the drive-roll, the aggregate diameter of said rolls being less than the circumference of the drive-roll, substantially as set forth. 75

In testimony whereof I have hereunto set my hand in presence of two subscribing witnesses.

CHARLES SUTTIE.
